UNITED STATES PATENT OFFICE.

WILLIAM A. WILLIAMS, OF BARTON, OHIO.

LENS FOR VEHICLE HEADLIGHTS.

Application filed September 26, 1925. Serial No. 58,781.

This invention relates broadly to head-lights for motor vehicles, and more specifically to a lens for such headlights.

The primary object of this invention is 5 to provide simple and efficient means for shielding the upper portion of a headlight reflector from direct rays from the therewith-associated lamp, thereby to prevent the collection in said upper portion of a 10 ball-like bundle of such rays which, reflected forward in a more or less solid beam, as ordinarily, would produce an objectionable dazzling glare.

A further object is to provide a headlight 15 lens which embodies as an integral part thereof a shield whereby light rays in objectionable volume are prevented from intercepting the upper portion of the headlight reflector with which the lens is associated.

In describing the invention in detail, reference is herein had to the accompanying drawings, in which—

Figure 1 is a central vertical section of a 25 vehicle headlight embodying my invention;

Figure 2 is a rear elevation of the invention; and—

Figure 3 is a section on line 3—3, Fig. 1.

Referring to said drawings, 1 indicates 30 generally the casing, and 2 the reflector of a vehicle headlight of a familiar type. Mounted within the front portion of the casing in any manner usual to or suitable for headlight lenses is a transparent glass lens 3 of generally flat form. Integrally formed on the rear face of said lens in the horizontal diametrical line thereof is a rearwardly-extending plate 4 of substantially flat horizontal form. Said plate, which 35 may either be made of colored glass or otherwise rendered translucent, as by frosting or by coating with paint or other appropriate substance, is designed to serve as a shield for preventing light rays from the filament of the lamp 5 from being concentrated in any considerable volume on the upper portion of the reflector, or in such volume as would be productive of a dazzling glare.

50 The lens 3 and said shield plate 4 are preferably formed together in a mold, and said plate, which is designed to lie wholly with-

in the enclosure constituted by the reflector, has its lateral edges 4^a inclined or curved to substantially conform to the curvature of the reflector, having its ends very closely approaching the walls of the latter, as shown. Said plate has its rearmost portion terminating in a line substantially parallel to the lens and located intermediate the 60 position of the lamp filament and the rearmost portion of the reflector. Thus, while the upper part of the reflector is shielded, as aforesaid, from the large volume of light rays which would otherwise impinge thereon, unobstructed passage of rays in such relatively small quantity or volume as serves to illuminate the upper part of the headlight, preventing the latter from appearing dark, is permitted, as indicated in 70 Fig. 1.

To provide for the accommodation of the lamp 5, the central rear portion of the plate is pressed into the form of a hood 6 which closely overhangs said lamp.

75 It will be noted that the structure described provides simple and effective means for obviating the objectionable glare of automobile headlights, while in no way obstructing or modifying those rays of light 80 which are either projected directly downward and forward upon the roadway, or which impinge upon the lower half of the reflector.

85 What is claimed is—

The combination with the lamp and the reflector of a vehicle headlight, of a transparent glass lens mounted in said headlight, said lens having formed on the rear face thereof an integral, non-transparent, substantially horizontal shield which extends rearward therefrom in substantially the horizontal plane of the axis of said lens and which has its central rear edge portion arched to form a hood which lies in overhanging relation to said lamp, said hood having its rear edge located rearward of the vertical plane of the filament of the lamp and at a substantial distance forward of the axial portion of the reflector.

100 In testimony whereof, I affix my signature.

WILLIAM A. WILLIAMS.
